UNITED STATES PATENT OFFICE

2,486,846

CAM ACTUATED SWITCH

Theodore Hetman, Los Angeles, Calif.

Application May 29, 1947, Serial No. 751,235

10 Claims. (Cl. 200—163)

1.

This invention appertains to novel and useful improvements in switches particularly adapted for use in automotive vehicles for the purpose of making and breaking the usual electrical circuit, when so desired.

Another object of this invention is to provide a pair of telescopically adjustable sleeve members having cam means therein for selectively lifting and lowering a rod.

Another object of this invention is to provide contact means within a selected sleeve for engagement with the lower portion of the said rod.

A further object of this invention is to provide means for electrically insulating the said contact from the said sleeve.

A still further object of this invention is to provide means for resiliently biasing the said selected sleeve relative to the anchoring means for said rod.

Another purpose of the present invention is to provide means for resiliently biasing a cover plate against the said selective sleeve, for the purpose of covering a guide slot therein.

Another purpose of the present invention is to provide improved actuating means for turning and reciprocating the said telescopically adjustable sleeve members.

Another purpose of this invention is to provide an improved and practical and inexpensive device of the nature described which is commercially feasible and which further, lends itself well to commercial manufacture and common shop practices.

Ancillary objects and features of novelty shall become apparent to those skilled in the art in following the description of the preferred embodiment of the present invention, illustrated in the accompanying drawings, wherein:

Figure 1 is a perspective view of the preferred form of the present invention showing the same used in the preferred environment;

Figure 2 is a longitudinal sectional view of the invention disclosed in Figure 1, with parts being shown in elevation to illustrate details of construction;

Figure 3 is a transverse sectional view of the invention disclosed in Figure 2 and taken substantially on the line 3—3 thereof and in the direction of the arrow;

Figure 4 is a perspective view of a cam utilized in the present invention;

Figure 5 is a perspective view of the anchoring means forming a part of the present invention;

Figure 6 is a front elevational view of a tube

2.

used in conjunction with the actuation of the present invention;

Figure 7 is a perspective view of the plate utilized in covering the guide slot forming part of the present invention; and

Figure 8 is a perspective view of a cam, complementary to the above mentioned cam which forms part of the present invention.

Referring now in detail to the illustrated preferred embodiment of the present invention, like reference characters are used throughout to indicate similar elements thereof.

This invention has been conceived and developed to provide a device for making and breaking the electrical circuit conventional in automotive vehicles and the like. Obviously, the utility of the present invention eliminates fire hazards, discharge of battery due to short circuits or grounds and provides an easy means to disconnect or render inoperative the conventional battery in order to work on or remove portions or elements of a vehicle employed in the usual electrical system.

A first sleeve 10 is provided with a shaft 12 extending therefrom. The said shaft 12 may be suitably secured to the said sleeve 10 by any conventional means such as welding, brazing, screw-threading or the like. A lug 14 is secured to the said shaft 12 extending therefrom. A detachable handle actuating means is provided for engagement with the said shaft 12. This handle means is composed of a tube 16 having a slot 18 extending longitudinally thereof with an enlargement 20 extending from said slot. This enlargement is utilized in receiving the said lug 14 therein, functioning as a bayonet latch. An actuating rod 22 extends through a suitable aperture 23 adjacent the upper portion of the said tube 16 and is utilized in supplying leverage. Means for resilient biasing the said tube 16 longitudinally of said shaft 12 is immediately ascertainable from an inspection of Figure 2. This resilient biasing means consists of a conventional coil spring 24 seated on a suitable shoulder 26, said shoulder being preferably integral with the shaft 12. It is noted however that the said shoulder 26 may be attached by any conventional means if so desired, in order to facilitate manufacture. The said resilient spring 24 seats on the shoulder 26 and also engages the lower extremity of the said tube 16.

A second sleeve 28 is telescopically received within the bore of the said first sleeve 10. It will be noted that the internal portion of the said second sleeve 28 is screw-threaded and a cam 30 is detachably secured therein. It may be noted

at this point that an annular groove is provided within the bore of the said sleeve 10, adjacent the lower extremity thereof. Positioned in the said groove is a sealing means, conventional in material, and is designated by the numeral 32.

A second cam, complementary to the said cam 30 is seen at 34 and has an aperture 36 in the side thereof. Means for securing this second cam 34 within the said sleeve 10 is provided. This means consists preferably of a simple bolt 38 extending through a suitable aperture (unnumbered) in the said sleeve 10. Of course, the bolt also extends within the threaded aperture 36 of the said cam 34.

A rod 40 extends through central apertures 42 and 43 respectively which are received in the said cams 34 and 30. This rod 40 may be in the form of a conventional bolt having the usual head 46 thereon. It will be seen from an inspection of Figure 2 that the said head 46 forms a stop and is engaged by a washer 48 which is in turn seated on the upper portion of the said cam 34. The stop engaging the washer 48 thus reacting on the upper cam 34, limits the longitudinal movement of said bolt with respect to said cams or cam members. The lower portion of the said bolt 40 is externally threaded as is conventional, and an anchoring means is secured thereto. This anchoring means is preferably a lug in the form of an eye bolt 50 having a threaded shank 52 extending therefrom. The said bolt 40 is threadingly received in the associated aperture in the said eye bolt and the shank 52 extends through a suitable slot 54 provided in the wall of the said sleeve 28. This slot 54 serves the purpose of limiting means in that it restricts the travel of the said sleeve 28 to motion parallel to the longitudinal axis thereof. A bearing block 56 is received on the bolt 40 and positioned above the said eye bolt 50.

Means for resiliently biasing the sleeve 28 relative to the eye bolt 50 or anchoring means is provided. This resilient biasing means consists of a relatively heavy coil spring 58 which is seated on the said bearing block 56 and which abuts the lower portion of the said cam 30. A plate 62 having a central aperture 64 therein is provided on the shank of the said eye bolt 50. This plate serves the purpose of a baffle for preventing fine matter from entering the switch. Means for resiliently biasing the said plate 62 against the sleeve 28 is provided. This means consists of the usual, conventional coil spring 64 engaging the said plate 62 and also engaging an adjustable anchor nut 66, rotatably and threadingly received on the shaft or shank 52. As is seen in Figure 1, the nut 66 is preferably engaged against a suitable automotive element 68 while the resilient biasing means engages the opposite face of said element 68.

A contact is provided in the lower portion of the said sleeve 28 and is preferably in the form of a bolt, conventional in nature. The said bolt is provided with a head 70 which serves the purpose of a contact, selectively engageable with the lower portion of the said eye bolt 50. The lower portion of the said bolt is conventionally threaded as at 72 for the purpose of receiving a nut 74 thereon, the threads 72 and nut 74 cooperating to form means for adjusting the head 70 longitudinally with respect to the longitudinal axis of the sleeve 28. Interposed between the head 70 and the said nut 74 is a plurality of elements. These elements are as follows: An insulating bushing 76, preferably of synthetic rubber or the

like, is seated within the said sleeve 28. It will be seen that the lower portion of the said sleeve 28 may be encircled to provide a shoulder 78 to assist in retaining the bushing 76 therein. A second resilient, insulating member 80 is placed exterior of said shoulder 78 while a disc or washer 82 is placed over said insulating member 80. The said nut 74 engages the said disc 82 thereby holding the assembly in an operative, fixed position.

In actuation of the invention, the handle 22 is rotated thereby turning the sleeve 10. This in turn rotates the cam 34 which abuts the complementary cam 30. Of course, the effective length of the rod 40 is then shortened. Since the rod 40 is relatively stationary due to the anchoring means 50, the sleeves 10 and 28 will be selectively extended or lowered, the limiting means or slot 54 controlling the direction of motion. It is quite apparent that upon a certain selected operation of the invention contact will be made between the member 50 and contact 70. Also, the contacts will be disengaged upon other selected positions of operation.

While there has been described and illustrated but a single preferred embodiment of the present invention, it is apparent to those skilled in the art that various changes may be made herein without departing from the spirit of the invention. Accordingly, limitation is sought only in accordance with the scope of the following claims.

Having described the invention, what is claimed as new is:

1. A switch comprising a first sleeve having a shaft extending therefrom, a second sleeve in the bore of said first sleeve, cam means secured to said first sleeve and complementary cam means secured to said second sleeve, a rod extending through both of said cam means, means for rotating said first sleeve to reciprocate said second sleeve, means for anchoring said rod and including a first contact, a second contact disposed in said second sleeve engaged by said first contact, means for resiliently biasing said second sleeve relative to said anchor means, means for insulating said second contact from said second sleeve, said first sleeve rotating means including a tube having a slot detachably received on said shaft longitudinally thereof, a lug secured to said shaft engageable with said slot and means for resiliently urging said tube in selected operative positions.

2. A switch comprising a first sleeve having a shaft extending therefrom, a second sleeve in the bore of said first sleeve, cam means secured to said first sleeve and complementary cam means secured to said second sleeve, a rod extending through both of said cam means, means for rotating said first sleeve to reciprocate said second sleeve, means for anchoring said rod including a first contact, a second contact disposed in said second sleeve and engaged by said first contact, means for resiliently biasing said second sleeve relative to said anchor means, means for insulating said second contact from said second sleeve, a slot in said second sleeve, said anchor means comprising a bolt extending through said slot, a plate on said bolt engaging said second sleeve and covering said slot and means for resiliently urging said plate against said second sleeve.

3. In a switch construction, a sleeve having a shaft extending therefrom, an extension detachably secured to said shaft, means disposed on said shaft for resiliently biasing said extension with respect to said sleeve, a second sleeve in the bore of said sleeve, a cam secured within the bore of said first-mentioned sleeve, a second cam

secured within the bore of said second sleeve and engaging said first cam, a rod extending through said cams, a slot in said second sleeve having an eye-bolt extending therethrough, said eye-bolt lockingly engaging one end of said rod, means seated on said eye-bolt and reacting on said second cam for normally biasing the sleeves telescopically relative to each other, means secured to the opposite end of said rod and engaging said first cam limiting the longitudinal movement of said rod through said cams, means for covering a portion of said slot, a contact secured to said second sleeve for engagement with said eye-bolt which forms a second contact, upon telescopic movement of said sleeves.

4. In a switch construction, a sleeve having a shaft extending therefrom, an extension detachably secured to said shaft, means disposed on said shaft for resiliently biasing said extension with respect to said sleeve, a second sleeve in the bore of said sleeve, a cam secured within the bore of said first-mentioned sleeve, a second cam secured within the bore of said second sleeve and engaging said first cam, a rod extending through said cams, a slot in said second sleeve having an eye-bolt extending therethrough, said eye-bolt lockingly engaging one end of said rod, means seated on said eye-bolt and reacting on said second cam for normally biasing the sleeves telescopically relative to each other, means forming a stop secured to the opposite end of said rod engaging said first cam to limit the longitudinal movement of said rod with respect to said first cam, means for covering a portion of said slot, a contact secured to said second sleeve for engagement with said eye-bolt which forms a second contact, upon telescopic movement of said sleeves, said slot covering means comprising a plate seated on said eye-bolt, means reacting on said eye-bolt and engaging said plate for normally biasing said plate against the outer surface of said second sleeve, and means for adjusting the last-mentioned biasing means.

5. The combination of claim 4, and said biasing means adjusting means comprising a threaded element received on said eye-bolt.

6. The combination of claim 4, an insulating element disposed in the lower portion of said second sleeve for preventing direct contact of the contact with the material of the sleeve, and means for adjusting said contact in said sleeve parallel to the longitudinal axis of said sleeve.

7. The combination of claim 4, an insulating element disposed in the lower portion of said second sleeve for preventing direct contact of the contact with the material of the sleeve, and means for adjusting said contact in said sleeve parallel to the longitudinal axis of said sleeve comprising a threaded shank secured to said contact, a threaded element disposed on said threaded shank reacting on the lower portion of said second sleeve.

8. A switch comprising a first sleeve having a shaft extending therefrom, an extension detachably secured to said shaft, and resilient means reacting on said extension and said shaft for constantly biasing said extension longitudinally with respect to said shaft, a second sleeve in the bore of said first sleeve, an upper cam secured to said first sleeve and a lower cam secured to said second sleeve, a rod extending through said cams and having means at one end engaging the upper cam limiting longitudinal movement of said rod in one direction with respect to said upper cam, means for anchoring

said rod at the end opposite said upper cam, a spring reacting on said last mentioned means and engaging said lower cam, a contact in said second sleeve engaged by said rod anchoring means which form a second contact, when said cams are moved relative to each other.

9. A switch comprising a first sleeve having a shaft extending therefrom, an extension detachably secured to said shaft and means for biasing said extension longitudinally with respect to said shaft, a second sleeve extensibly connected with said first sleeve, a first cam secured to said first sleeve and a second cam secured to said second sleeve, a rod extending through said cams and having a head at one end engaging said first cam to limit longitudinal movement of said rod in one direction with respect to said first cam, a bolt secured to said rod for anchoring the opposite end of said rod, a contact disposed in said second sleeve and engaged by said bolt, which forms a second contact, means for resiliently biasing said second sleeve relative to said anchor means, means for insulating said first mentioned contact from said sleeves, said second sleeve having a slot, said bolt extending through said slot, a plate engaging said second sleeve and overlying said slot, and means engaging said plate and reacting on said bolt for normally biasing said plate against said second sleeve.

10. In a switch assembly, a first sleeve having a bore with an open end, a second sleeve slidably disposed in said bore and passed through said open end, a shaft secured to the end of said first sleeve opposite said open end, an extension, means releasably fastening said extension to said shaft, an upper cam member secured to said first sleeve and disposed in said bore, a lower cam member secured to said second sleeve and contacting said upper cam member, said cam members being so shaped that relative rotation of said cam members causes relative longitudinal movement of said sleeves, a rod disposed in said second sleeve and having a stop secured thereto engaging said upper cam member limiting longitudinal movement in one direction of said rod with respect to said upper cam member, said second sleeve having a lateral opening, an anchor member passed through said lateral opening and secured to said rod, a spring reacting on said anchor member and said second sleeve constantly urging said second sleeve in such direction as to pull said stop against said upper cam member, said anchor member forming a first contact, a second contact secured to said second sleeve and engageable with said first contact when said second sleeve is moved inwardly in said bore.
